MAGNETIC TAPE UNIT OR SIMILAR ARTICLE

Roy A. Blom, 143 Monroe St., Massapequa Park, N.Y.

Filed Sept. 27, 1963, Ser. No. 76,762

Term of patent 14 years

(Cl. D26—5)

The single figure is a perspective view of a magnetic tape unit or similar article, showing my new design.

The characteristic features of my new design are shown in solid lines in the drawing and reside in the two panel-mounted, vertically disposed vacuum tanks substantially centrally located, combined with the flanking tape reel spindles and information processing tape head assembly.

The tape reels shown in broken lines are for purposes of illustration only.

I claim:

The ornamental design for a magnetic tape unit or similar article, as shown and described.
